(57) **CLAIM**

The ornamental design for a heater face trim, as shown and described.

DESCRIPTION

FIG. 1 is a front perspective view of a heater face trim showing our new design;

FIG. 2 is a left side elevational view of the heater face trim;

FIG. 3 is a right side elevational view of the heater face trim;

FIG. 4 is a front elevational view of the heater face trim;

FIG. 5 is a rear elevational view of the heater face trim; and, FIG. 6 is top plan view of the heater face trim, the bottom plan view being a mirror image thereof.

The broken lines shown in FIG. 1 are for the purpose of illustrating environment and form no part of the claimed design.
